Primary Examiner — George D. Kirschbaum*Assistant Examiner* — Lillian Windham(74) *Attorney, Agent, or Firm* — GRUMBLES LAW PLLC; Brittany Haanan(57) **CLAIM**

The ornamental design for a base for a standing scoreboard, as shown and described.

DESCRIPTION

FIG. 1 is a perspective front view of a base for a standing scoreboard showing our new design.

FIG. 2 is an elevational front view of the base for a standing scoreboard.

FIG. 3 is an elevational back view of the base for a standing scoreboard.

FIG. 4 is a top plan view of the base for a standing scoreboard.

FIG. 5 is a bottom plan view of the base for a standing scoreboard.

FIG. 6 is an elevational right side view of the base for a standing scoreboard; and,

FIG. 7 is an elevational left side view of the base for a standing scoreboard.

The broken line showing of a standing scoreboard is included to illustrate environment of the invention and forms no part of the claimed design. The broken line showing of wing nuts are included to illustrate parts of the base for a standing scoreboard which form no part of the claimed design.
